UNITED STATES PATENT OFFICE.

MATTHEW NESELER, OF KANSAS CITY, MISSOURI.

ELECTRIC FAN.

1,194,413.

Specification of Letters Patent. Patented Aug. 15, 1916.

Application filed July 8, 1914. Serial No. 843,799.

To all whom it may concern:

Be it known that I, MATTHEW NESELER, a citizen of the United States, residing at Kansas City, in the county of Jackson and State of Missouri, have invented a new and useful Electric Fan, of which the following is a specification.

This invention relates to improvements in electric fans and more particularly to a fan guard and supporting pedestal therefor.

One object of the present invention is to provide an electric fan which may be folded so as to occupy but little space allowing it to be conveniently carried about or packed within a small space for economic transportation.

A further object of the invention is to provide a coöperating fan guard and pedestal, whereby the pedestal will be maintained in a folded condition and so held by a fan guard.

A still further object of the invention is to provide a pedestal including a tripod base which may be easily secured to a bed post, or window sill, or may support the fan in the usual manner.

A further object of the invention is to provide a fan with a folding guard which is adapted to fold against the cylindrical body of the fan and to provide the fan with folding blades or paddles allowing the entire device to be folded to occupy little space and thus rendering it conveniently portable and economically transportable.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a view in side elevation of my improved electric fan, with a supporting pedestal rotated slightly out of and perpendicular to the vertical plane of projection. Fig. 2 is a front view of the fan. Fig. 3 is a view similar to Fig. 1 with the pedestal, fan guard, and fan blade folded. Fig. 4 illustrates in section one of the folding members of the fan guard. Fig. 5 is a view in section of the pedestal and illustrating its connection with the body of the fan.

Referring to the drawings in which similar reference numerals designate corresponding parts throughout the several views, the electric fan includes a cylindrical body or casing 6 through which extends the usual fan carrying shaft 7.

A tripod 8, including the two stationary legs 9 and a movable leg 10, forms a part of the pedestal for the support of the fan, and through the instrumentality of the movable leg 10 and the holding set screw 11 therefor, allows the fan to be supported in the usual manner or clamped to a bed post, window sill, or equivalent structure. A standard 12 is provided with the hinged joint 13 intermediate its ends into which extends the wing bolt 14 whereby the joint may be rigidly locked in adjusted position. The upper extremity of the standard is provided with the slot 16 which prevents the standard from becoming detached from the sleeve 15 to which it is rotatably secured. The sleeve 15 is rigidly secured to the body 6 and mounts the same upon the pedestal. The sleeve is provided with the rearwardly extending slot 18 allowing the standard to collapse as illustrated in Fig. 3, but normally prevented from such movement by the weight of the fan.

The ring 20 embraces and is rigidly positioned upon the body 6 and includes a plurality of outstanding flanges 21, arranged in pairs and to which the securing arms 22 are pivotally secured. Each of the said securing arms is provided with the rearwardly extending foot 23 through which the pivot 23' extends, thus limiting the movement of the securing arm in one direction, to the position illustrated in Fig. 1, the direction in question being clockwise in the said figure. A plurality of cross bars 24 are hingedly secured to the upper and offset extremities of the securing arms 22 and with the joints 25 therebetween limiting the movement in one direction. Pivotally secured to the cross bars 24 are the front rods 26 normally extending down across the front of the fan and thus coacting with the cross bars and securing arms to form a complete protecting guard. The front rods are pivotally secured as at 27 to the cross bars and are provided at their lower extremities with the lugs 28 which are held spaced apart by reason of the various joints 27—25, and the joints between the supporting arms and the ring 20. By these means the lugs 28 at the

lower extremities of the front rods 26 will be normally held in spaced relation and allow the ring 30 to be resiliently sprung within the groove 29 with which the lugs 5 are provided. With the ring so positioned, the guard will be a rigid structure and capable of protecting and housing a fan 31 therein. On the other hand when the ring is removed, the front rods, cross bars and 10 securing arms may be rearwardly folded.

The fan 31 is mounted upon and rotated by the shaft 7 and includes a plurality of blades 33 which are provided with the tips 32 hinged to the main portion of the blade 15 as at 33 whereby the blades may also be rearwardly folded as illustrated in Fig. 3. The provision of the rearwardly folding frame and blades provide that the fan may be folded to occupy little space, thus rendering it conveniently portable and economically transportable. The pedestal may be also rearwardly folded and held in such position by the front rods 26 when in their folded position. The hinge connections 33 20 of the fan blades are made exceedingly stiff which prevent the fan blades from being forced rearwardly by the forward propulsion of air which effect, it is to be noted, is also counteracted in a large measure by the 25 centrifugal force of the rotating fan. The stiff hinge also provides that the blades having been collapsed as illustrated in Fig. 3 will rest upon and bear against the securing arms 22 and hold the same in a collapsed 30 position, which in turn holds the pedestal standard folded as illustrated. This entire device having been once folded will retain such position allowing it to be conveniently handled and carried about. The resiliency 35 of the securing arms 22, cross bars 24, and front rods 27 insures that the ring, having once assumed the position within the groove 29 will remain securely so locked.

Having thus fully described the invention 40 what I claim is:

1. In a device of the character described, a body, a rotary fan carried thereby, and a collapsible fan guard carried by the body and foldable thereagainst away from the 45 plane of rotation of the fan.

2. In a device of the character described,

a body, a rotary fan carried thereby whose blades have tips foldable away from the plane of rotation of the fan against the body, and a collapsible fan guard carried by the 55 body and foldable thereagainst in a direction similar to said tips.

3. In a device of the character described, a body, a rotary fan carried thereby whose blades have tips foldable away from the 60 plane of rotation of the fan against the body, a collapsible fan guard carried by the body and foldable thereagainst in a direction similar to said tips, and a foldable supporting member for the body foldable adjacent the 65 same.

4. In a device of the character described, a body, a rotary fan carried thereby, and a fan guard carried by the body embodying supporting arms pivoted to the body foldable rearwardly against the body away from the plane of rotation of the fan, front rods pivoted to said arms, and means for detachably securing said rods together. 70

5. In a device of the character described, 75 a body, a rotary fan carried thereby and a collapsible fan guard carried by the body embodying pivotally connected sections foldable rearwardly against the body away from the plane of rotation of the fan, and means 80 for fastening them together when they are unfolded.

6. In a device of the character described, a body, and a fan guard carried thereby embodying arms pivoted to the body, cross elements pivoted to said arms, front rods pivoted to said elements, said arms, elements and rods having limited swinging movements relative to one another whereby they are held in place when they are unfolded. 85 and a ring engageable with said rods to hold the guard in place when unfolded.

7. A fan body having a fan and fan guard each foldable against the body away from the plane of rotation of the fan. 95

In testimony that I claim the foregoing as my own, I have hereto affixed my signature in the presence of two witnesses.

MATTHEW NESSELER.
